UNITED STATES PATENT OFFICE.

THOMAS JAMES DAVIS, OF NEW YORK, N. Y.

RECEIVER FOR ABRASIVE GRINDINGS OR DUST.

1,177,023.

Specification of Letters Patent. Patented Mar. 28, 1916.

Application filed June 16, 1915. Serial No. 34,496.

To all whom it may concern:

Be it known that I, THOMAS J. DAVIS, a citizen of the United States, and resident of the borough of Brooklyn, county of Kings, city and State of New York, have invented certain new and useful Improvements in Receivers for Abrasive Grindings or Dust, of which the following is a specification.

This application is one of a series which have for their purpose the development of certain improvements in relation to the use of abrasive wheels and in this application I will set forth and describe what I term a dust box, but which is the receptacle into which the refuse from the grinding wheels shall be deposited and retained.

In developing this invention I have had in mind the production of a grinding attachment particularly useful to dentists and others who for obvious reasons desire that the operation of grinding shall be as cleanly as possible and shall conserve and preserve all of the material which is cut away by the action of the abrasive wheel from the article being ground.

It will be understood that in the making of artificial teeth much gold is used and that it is quite necessary to grind and polish the surfaces of the gold and to cut away certain portions of the surface so that the final result shall be the production of teeth attractive in appearance and of proper contour.

In the past it has been found difficult to recover the gold which has been ground away as the process of grinding will often remove small particles of enamel and of rubber used in the production of the teeth and gums and also small portions of the abrasive material and moistening tool or device which may become mixed with the gold to an extent that makes its separation impractical for the operator as the separation can only be accomplished by means of a retort in a manner well understood. Now, however, I produce a receptacle or dust box which will receive all of the material ground away together with the small particles of abrasive, and I so construct my dust box that it may be used as a cradle or pan by means of which refuse material may be washed away, and the gold, which is of greater specific gravity, will remain in the bottom of the box. I also provide adjustable support for my dust box and means which will adapt it to serve with abrasive wheels of different diameters.

The construction, method of operation and the advantages to be derived from this invention, will be fully set forth as the specification progresses. 60

The following is what I consider a good means of carrying out this invention and the accompanying drawings form a part of this specification, in which— 65

Figure 1 is a front elevation of my completed device. Fig. 2 a plan view thereof. Fig. 3 a side elevation of certain parts. Fig. 4 a fractional view, in perspective, of a part removed. 70

Similar reference numerals indicate like parts in all of the figures where they appear.

My improvements are operable with a device commonly termed a grinding lathe 75 which consists of a small electric motor as indicated at 1, the shaft of which, passing through the bearing member indicated at 2, terminates in an arbor 3, upon which an abrasive wheel 4 may be secured. 80

Motors of different sizes are used and as the bearings 2 are not of uniform diameter I provide an adjustable clamp adapted to engage bearings of different diameters and by means of which my devices are supported in operable position. The clamp is formed of two engaging parts, a finger 5 being in pivotal engagement with a block 6; the free end of the finger 5 is offset as indicated at 7, so that it will not interfere either with the 85 lubricating device 8 or with any other member which may be attached to the bearing 2.

Pivotedly secured to the block 6 I arrange a plurality of L shaped members 9 and 10 one on each face of the block 6 and each secured thereto by means of a readily removable screw. The block 9 adjustably supports a rod 11 to which is secured a moistening device 12. Through the right angled projection 13 of the block 10 I pass a rod 14 and adjustably retain it in the projection 13 by means of a thumb screw 15. The rod 14 is L shaped and upon the lower horizontal extension of this rod 14 I support the member that I refer to as the dust box. 95 100 105

The dust box 16 is provided with a plurality of clamps 17 and 18 through which the rod 14 passes and I may provide means as a screw 19 for securing the clamps to the rod 14. The exterior outline of this dust box may be of any shape or contour but the interior of the box should be smooth and without sharp corners so that it may be readily cleaned by flushing. 110

- Within the box I arrange a plurality of transverse barriers 20 and 21 which may be deep corrugations. I prefer that the valleys between the corrugations should be rounded 5 at the bottom, but the apex of each corrugation should be contracted so as to present but little surface to the falling material to be received in the box. It will be noted that the upward projections of the corrugations 10 do not extend to the top of the box, and it is my intention that they shall be lower than the line of a series of perforations 22 which I provide in one of the sides of the box for a purpose that shall appear later. Through 15 the perforations 23 in the longer sides of the box I pass a pin 24 and upon this pin I engage a cover formed of two parts as indicated at 25 and 26. The cover when extended will close the entire top of the box or may 20 even project beyond the end thereof. When, however, the device is in operative position as shown in the figures, the cover is raised and serves as a means for deflecting the material thrown off by the abrasive wheel 4 25 causing the material to fall into the box and to be retained therein. The telescope of the cover enables it to be used with equal satisfaction with abrasive wheels of different diameters.
- 30 When considerable material has collected in the dust box 16, I may remove the box by releasing the screws 19. I may then fill the box with water and by a slight rocking movement wash away the foreign matter in 35 the box, allowing the gold or other metals to be deposited in the bottom of the box. By additional quantities of water I may completely pan the gold so that the residue will be only such materials as I may desire to 40 retain. By the use of this box and by panning the contents thereof I retain not all of the material thrown off by the wheel but only such portions as are of great value. It is obvious that the panning may be dispensed with, as the waste material, all of 45 which will be collected in the dust box, will have a ready sale even in its adulterated form.
- I have shown a peculiarly formed clamp 50 and an adjustable moistening device the construction of which will be claimed in another application.
- It is obvious that my dust box may be used without the clamp or the moistening device, 55 and the box would have certain advantages even though the supporting means that I have shown and described in connection therewith were omitted.
- I call attention further to the interior corrugations that not only serve the useful purpose in the operation of panning but are so proportioned and arranged that when a

large piece of material accidentally leaves the hand of the operator and falls into the box it will not pass to the bottom of the box 65 there to mix with the damp matters collected by the box but will rest upon and across the tops of the corrugations where it may be readily removed in a clean condition.

Other modifications may be made within 70 the scope of the appended claims without departing from the principle or sacrificing the advantages of this invention.

Having carefully and fully described my invention, to the best of my ability, what I 75 claim and desire to secure by Letters Patent is—

1. The combination with an abrasive wheel of a dust collector having a hinged and telescoping cover and means for adjustably supporting said dust collecting means adjacent to an abrasive wheel as and for the purpose set forth. 80

2. The combination with an abrasive wheel of a moistening means and a dust collecting 85 means and means for rotating the moistening and dust collecting means out of operative position as and for the purpose set forth.

3. The combination with an abrasive wheel 90 of a dust collector, means comprising a box having a plurality of corrugations upon the interior thereof, and means for adjustably supporting said box in operable position as herein specified. 95

4. A dust collecting box provided with a plurality of perforations through the side thereof and having a plurality of interior corrugations and means for supporting said box as and for the purpose set forth. 100

5. A dust collecting box provided with a plurality of perforations and having a deflector hingedly engaged with said box and adapted to operate therewith as and for the purpose set forth. 105

6. A dust collecting box provided with a plurality of perforations through the side thereof and a telescoping deflector secured thereto, and means for adjustably supporting said box in operable position, as and for the purpose set forth. 110

7. A device of the character described comprising a box member the sides of which are perforated, and having corrugations within said box adapting it to serve the double 115 function of a dust collector and panning device as and for the purpose set forth.

Signed at New York city, county and State of New York this 11th day of June, 1915, in the presence of these two witnesses. 120

THOMAS JAMES DAVIS.
